FIG. 3.

UNITED STATES PATENT OFFICE

2,330,531

MEANS FOR IDENTIFYING DOCUMENTS

Adolph F. von Soden, Long Beach, Calif.

Application October 6, 1941, Serial No. 413,855

4 Claims. (Cl. 283—7)

My invention relates to a positive identification of the documentary instruments and records and more particularly to the identification of legal instruments which have thereon the signatures of contractual participants, signatories to wills and testaments, personal identifications, witnessed documents, affidavits, depositions, oaths, including identifications of notary public seals and the like, and which in their usage serve the purpose for positively identifying the person or persons who have or are signing the instruments, and thereby preventing any fraud, falsifications, forgery or misrepresentation in and to all such legal and personal papers, records or documents, as may any time or in future be brought before or used in courts, judiciary tribunals or other institutions demanding a positive and a definite identification of the person or persons who have personally executed or witnessed such documentary papers, records, or instruments in writing.

Manifestly, an object of my invention is to provide a documentary paper in sheet form, having a suitable place for affixing the signature thereon, or in case of one who is not able to write or is disabled in some manner, or those using "X" mark system, such paper having a space designated for the express purpose for affixing along with said signature or a mark, an imprint of a finger or other part or portion of a skin or body, which is definitely identified by a witness, such print to be a thumb, fore-finger, toe or the like, and which is to be a permanent record thereof and be recognized as a positive and indisputable evidence of the proper person, whose signature and the identity to such document is sought to be established.

Accordingly an object of my invention is to provide a suitable paper in sheet form, which is provided with suitable indications printed thereon for utilizing same for the finger print marks and also to provide suitable indication marks which are to be used for and by the notary public for their seals and also having suitable place marked for the uses by witnesses, so that a positive identification may be had.

Further object of my invention is to provide said paper sheet with a suitable pad member and which is attached thereto, said pad being folded over and closed entirely and only opened when same is in readiness for use by the person whose signature is to be verified and counter-checked as to the proper and the identical person or persons.

Another object of my invention is to provide said sheet of paper having a chemically treated section or suitable portion, said chemically treated section to be used for imprinting thereon said finger-prints and also to prevent erasures or other falsifications of the document or the finger-print so affixed thereto, also will prevent its destruction by fire or other element and thereby establishing a positive and an unquestionable identity of the signatures and the persons who are the parties mentioned in said document.

Further object of my invention is to provide said sheet of paper with a suitable chemical, or a combination of suitable chemicals, which may be sprayed thereon after the signature is affixed to a document and the finger-print is deposited in its proper place for identifying said signature which is for the purpose to prevent any falsification of said signatures or the prints and also to prevent the use of any other neutralizing agent for changing such signature or print, which in such case will cause said paper to change color when an erasure or a removal of the signature or finger print is attempted, thus preventing any replacement of the signature or print and thereby removing any possibility of tampering with documents and the authenticity of signatures.

Other and further objects and advantages of my invention as will hereinafter more fully appear, I attain by the arrangements of the elements involved, described and shown on the drawing, forming a part of my application.

Reference is had to the accompanying drawing in which the similar reference characters denote the similar parts.

In the drawing.

Fig. 1 is the plan view of the sheet of paper, showing the approximate positions of the markings which are used for affixing the signatures and the identifying imprint of the finger.

Fig. 2 is the fragmentary layout view of the paper sheet showing the position of the pad member which is folded over and which is detachably connected therewith, said pad being provided with the finger-print transposing chemical, same being shown in modified form.

Fig. 3 is the cross sectional view of the pad member, taken on the line 3—3 of the Fig. 2.

Fig. 4 shows the sheet of paper having a detachable folded over pad member and having its surface treated with chemical which is invisible and will change the paper color upon application of a reagent or chemical erasure solution, said paper also having markings directing the posi-

tions of the signatures and the finger-printing for the signatories and the notary public, including the seal, same being shown in another modified form.

Describing my invention more in detail, in its broader aspects, said invention comprises a sheet of paper generally designated by numeral 2 which at its lower right hand section 4 is provided with a plurality of lines 6 each of which is provided with a circular marking 8 and directly thereabove having an identification in printed form for designating the particular finger imprinted in said circular marking 8 of the person whose signature is written over the line 6.

Also, said sheet of paper 2 at the lower left hand corner 10 is provided with a line 12 designating the position where the signature of the notary public shall be, also having a circular marking 14 for the finger-print and the identification 16 of said finger directly thereabove or in some other place as in practice may be most desirable, including having a suitable marking such as "LS" or the like which is used for directing the position of the notary seal and designated by numeral 18.

In order to place the finger-print upon the paper and within said circular marking 8 any suitable solution, chemical composition, paste or printing medium may be used and thereby positively identifying the signature of the person which is affixed upon the designated line 6.

Also, in order to prevent falsifications of signatures, forgery of signatures and misrepresentation of persons or individuals whose true signature appear upon a legal document or other instrument, therefore it is within the province of my invention to provide any and all legal or other papers requiring the signatures of persons whose names are or to be affixed thereto, with the circular or other suitable marking 8 which shall be used for placing the finger print thereon.

In the event the properly prepared printing ink, pad, paste or the printing medium is not available for immediate use, then another type of paper sheet may be used, as shown in Figs. 2 and 4 which is provided with a folded over and a detachable pad member 20, one surface section of which, as at 22 is provided with a thin layer of suitable chemical, printing ink or the like as at 24 and which if so desired may be folded over as shown, see Fig. 3, and be held in place by means of suitable and gummed tape 26 so that same may be easily removed and the pad member unfolded, thus exposing the inked or chemically prepared surface 22 and which after its use may be detached and suitably dispensed with.

In this manner as herein described, said sheet of paper 2 is provided with means in a form of a pad which is folded over and partially sealed and which will not dry-up or become destroyed even though said sheet 2 is laid away for a time, said pad surface having the chemically treated ink of such consistency which may be easily refreshed with a light solution of alcohol, ether, acetic acid or the like and thereby providing a finger-printing pad for immediate use.

In order to prevent the erasures, removal or otherwise destroying or falsifying the signatures, finger-prints or other identifying indicia upon legal documents, legal instruments, wills, testimonials and the like, said paper sheet 2 is provided with a chemically treated surface, as shown in Fig. 4 and designated by numeral 28, or, if so

desired the entire paper surface 30 may be so treated.

The chemical solution used in treating paper surface 30 or any suitable portion thereof is composed of the following, to-wit: Ammonium phosphite one gram, phenolphthalein one gram dissolved in aqueous (1%) solution of uranine (sodium salt of fluorescein) adding the combine solutions to 100 c. cm. of a 10 percent solution of potassium chloride, then the combine solutions are added and mixed in a distilled water in proportions of 5 to 1 by volume.

It may be then noted that in the event said paper sheet 2, so treated with the combination of chemicals hereinabove named is dry, the surface thereof will not be destroyed and will not blur the ink in the event a pen and ordinary ink is used for writing thereon or for affixing the signature as hereinbefore described, and that the imprint of the finger will be clear and legible, however, in the event said paper is subjected to a chemical treatment, chemical erasing fluid, erasures or electro-active chemical solutions, then the paper's surface will change the color to light yellow and bright red which will indicate definitely that said signatures, writings and the finger-print impression had been tampered with and will further prevent to place an eligible signature or a finger-print in its place.

It may also be noted that said paper sheet 2 in treated or un-treated form may be used to receive thereon an imprint of the finger-print by using the common writing ink, by first cleaning the finger with a solution such as alcohol and then applying a light coating upon the finger surface and finally by applying said ink coated finger upon the paper and at its place so designated, which will cause the ink to penetrate into the paper body and thereby preventing its removal irrespective of the erasing method or form which may be used for that purpose.

While I have thus described my invention with great particularity, it will be clear that the same may be modified throughout a wide range.

I accordingly do not propose to be limited to the exact details of line and marking designation, or the combination of the chemicals nor the application of the chemicals upon the paper surface or the paper pulp used in its manufacture, but reserve the rights in practice to make any and all changes and modifications therein, which may come within the scope of the appended claims.

I claim as my invention:

1. A sheet of paper of the class described, having a plurality of signature line means on said paper for placing signature thereon, also having marking means at each signature line means for affixing finger-print imprint therein, and a folded over finger print pad means which is detachably connected to said sheet of paper for supplying the finger-print ink for each finger-print mark, a gummed tape means at the folded over edge of said pad means for holding the pad edge in folded over position and upon said sheet of paper, and perforations lying parallel to said folded over edge of said pad and passing through said gummed tape means and said sheet of paper at the point adjacent thereto, for detaching said pad from said sheet of paper when not in use.

2. A sheet of paper of the class described, having a plurality of signature line means printed upon said paper, also having a plurality of finger-print marking means on said paper and disposed in opposition to said signature line means, and

an addition having seal marking means including finger-print marking means and signature line means at one edge of said paper reserved for official signature and for identifying the signatures and the finger-print imprints of the signatories, a plurality of perforations lying parallel to the edge of said sheet of paper for defining a pad means, a finger print coating layer disposed upon the surface of said defined pad means for lying between said pad means and said sheet of paper when folded over and at the demarcation line of said perforations, a gummed tape means lying parallel to and upon the folded over edge of said pad means for holding said pad means in its folded position upon said sheet of paper and for sealing said finger print coating layer therebetween.

3. In a detachable finger printing pad of the class described adapted to be a detachable part of a sheet of paper, comprising, a folded strip of

paper defining a width of said pad, a coated layer of finger print ink disposed between said folded strip of paper, a gummed tape means at the top edge of said folded strip of paper for sealing said strip upon said sheet of paper into a pad, and perforation means in said gummed tape means and said sheet of paper in close proximity to the edge of said folded strip for detaching said pad.

4. In a detachable finger printing pad of the class described adapted to be a detachable part of a sheet of paper, comprising, a folded strip of paper defining a width of said pad, a plurality of perforations at the folded edge of said folded strip, a coated layer of finger printing ink disposed upon the surface of said folded strip, and a gummed tape means at the top edge of said folded strip for sealing said strip upon said sheet of paper into a pad.

ADOLPH F. VON SODEN.
